(57) **CLAIM**

The ornamental design for a folding mount for tablet computer, as shown and described.

DESCRIPTION

FIG. 1 is a rear isometric view of a folding mount for tablet computer according to the invention, with a tablet computer interface member depicted in broken lines;

FIG. 2 is a front isometric view of the folding mount for tablet computer depicted in FIG. 1;

FIG. 3 is a front elevation view of the folding mount for tablet computer depicted in FIG. 1;

FIG. 4 is a side elevation view of the folding mount for tablet computer depicted in FIG. 1;

FIG. 5 is an opposing side elevation view of the folding mount for tablet computer depicted in FIG. 1;

FIG. 6 is a rear elevation view of the folding mount for tablet computer depicted in FIG. 1; and,

FIG. 7 is a top plan view of the folding mount for tablet computer depicted in FIG. 1.

The portions of the figures rendered in broken lines form no part of the claimed invention.
